APPARATUS FOR VAPORIZING LIQUIDS

Solon Alexander Daveron, Rio de Janeiro, Brazil

Application July 1, 1938, Serial No. 216,925
In Brazil July 3, 1937

4 Claims. (Cl. 299—88)

My invention relates to an apparatus for vaporizing liquids; more particularly, it relates to a simple, compact, portable type of vaporizer in combination with a container for liquids to be vaporized. Certain types of apparatus of this character, heretofore constructed for the vaporization of insecticides, paints and other liquids present difficulties in transportation because inadequate provisions have been made for preventing the leakage of their liquid contents. This is a serious disadvantage encountered by travelers who would like to carry such an apparatus in a suitcase or trunk containing clothes or other objects that are subject to damage by liquids. Other disadvantages associated with certain forms of portable vaporizers include liability to failure of vital parts thru wear, following prolonged use and oxidation and/or corrosion of vital parts thru contact with the atmosphere. Furthermore, loss of liquid contents thru evaporation and decomposition or other changes in the qualities of the liquid contents may be expected in such types of portable vaporizers as do not provide for the adequate sealing of the apparatus when it is not in use. In addition, many types of portable vaporizers, being awkward in shape, are easily overturned and require both care and excessive space in storage.

It is the object of my invention to provide an improved apparatus of the character referred to in which such disadvantages as those mentioned above are avoided and which is of simple construction, efficient in operation and inexpensive to manufacture.

Another object of my invention is to provide an apparatus of the character referred to that will reduce the physical effort required to vaporize a given amount of liquid by utilizing the relatively large volume of air which any normal operator of my invention is capable of exhaling. My invention will be better understood from the following description taken in connection with the accompanying drawing and its scope will be pointed out in the appended claims.

Figure 1 is a superior view of the head of the vaporizer with tube in position for use.

Figure 2 is a cross section of the cap used in closing and sealing the vaporizer.

Figure 3 is a lateral view of vaporizer with tube in position for use.

Figure 4 shows valve assembly.

Figure 5 is a cross section of the vaporizer in the container and ready for use.

Figure 6 is a cross section of vaporizer in the container, closed and sealed.

As can be seen by observing the above figures, my invention consists of the following parts: a round, externally threaded head 1 with a vertical shoulder 4 which has in its center a threaded hole; a short tube 2 inserted into the head from

above and serving, superiorly, as an outlet for liquids and, inferiorly, as the seat of a valve; a tube 7 inserted into the head 1 from below and in line with tube 2 serving to convey liquids from the lower part of the container 12 to the external opening of the tube 2; a ventilating hole 2a thru the head 1; a tube 5 sealed at its lower extremity, extending downward thru the head 1 whose function it is to receive tube 6 when the apparatus is being sealed; a tube 6 threaded at one end, to enter shoulder 4 of head 1; a base 10 threaded exteriorly to receive cap 8 and interiorly to receive head 1 and having a flange 11 at its lower extremity; a gasket 14; a cap 8; a container 12 to which base 10 is fixed; and a valve assembly 13.

To operate this vaporizer, the head 1 is screwed into the base 10 until its upper surface is flush with the top of the base 10. The tube 6 is then screwed into the hole in the shoulder 4 of the head 1. Now by blowing into, or applying any other source of air under pressure to the free end of tube 6, a current of air is forced around and past the external opening of tube 2 causing a rising of liquid from the container thru tube 7 and thru tube 2 and the vaporization of this liquid in the stream of air directed thru tube 6. It will be observed in Figure 5 that the valve assembly 13 rests upon the bottom of the container 12 and that the ball 13a is well below the seat at the bottom of the tube 2 thus permitting a free passage of liquid from the container to the external opening of tube 2. It is also to be observed that the vent 2a permits the entrance of air into the container while the head 1 is in this position.

To close and seal the apparatus. Tube 6 is unscrewed from shoulder 4 and placed in tube 5. The cap 8 is placed in position over base 10 so that the inner threads of the cap 8 engage the external threads of the base 10. Once the threads become engaged, the two pegs 9 of the cap 8 come into contact with the shoulder 4 of the head 1 and a continued turning of the cap 8 imparts a rotary motion to the head 1 causing its descent into the base 10. As the inner and the outer threads of the base 10 are of the same pitch, the head 1 descends evenly with the cap 8 until it rests upon the gasket 14. Added force applied to the turning of the cap 8 compresses the gasket 14 between the head 1 and the flange 11 thus stopping vent 2a and also preventing the escape of any liquid by way of any space between the threads of head 1 and the inner threads of base 10. It will be observed, Figure 6, that with the descent of the head 1 the space between the seat at the bottom of tube 2 and the ball 13a becomes eliminated and that the ball 13a comes into contact with the seat under pressure supplied by the compression of spring 13b thus preventing escape of liquid thru tube 2. The va-

porizer is now (Figure 6) effectively sealed within its container 12 and the liquid contents of the container 12 cannot escape regardless of the position in which the apparatus is stored or carried.

It will be seen that my vaporizer can readily be transferred to any other properly constructed container provided such other container is equipped with a base 10 and provided, further, 10 that the length of the tube 7 and the valve assembly 13 be changed, if necessary, to conform to the height of the new container.

To open and unseal the apparatus, the process of closing and sealing, as described above, is 15 simply reversed.

Having now particularly described and ascertained the nature of my said invention and in what manner the same is to be performed, I declare that what I claim is:

20 1. An atomizer assembly comprising in combination an outer cylindrical housing member having an inwardly presented flange adjacent the bottom thereof, a central head fitting within and adjustable axially in said housing, a closure cap member adapted to close the top of said housing and to cause the central head to come into engagement with said flange, a liquid-conveying tube extending through said central head and fitted with a valve mechanism adapted to close 25 the tube on engagement of the head and the flange, an air vent through said head so positioned as to be closed on engagement of the head and the flange, and an air tube removably fixed to said head and adapted to deliver air across the upper opening of said liquid conveying tube.

2. An atomizer assembly comprising in combination an outer cylindrical housing member having a threaded inner cylindrical surface, an exteriorly threaded portion adjacent the top thereof of, and an inwardly presented flange adjacent the bottom thereof, an externally threaded central head in screw engagement with the inner threaded surface of the housing member and adjustable axially by rotation therein to engage the said 45 inwardly presented flange, said central head having an air vent extending substantially vertically therethrough, the lower opening of which is in alignment with said flange, said head further having a vertically projecting substantially centrally located shoulder through which is disposed a laterally extending passage, an elongated tubular member extending vertically through said head and having a constriction in its upper end portion which projects above the head to provide 50 a liquid passage of smaller diameter than that of said tubular member and to provide an inwardly disposed valve seat, a valve member adapted to engage said valve seat and effect a closure of the tubular member when the said central head is brought into engagement with the housing flange, an air-conveying tubular member one end of which is adapted to fit within the lateral passage in the shoulder portion of the central head and to pass air across and at an angle to the 55 constricted passage in the tubular member, and a threaded closure cap adapted to engage the exterior threads on the cylindrical housing, and further adapted to engage the central head and by rotation to bring said head into closure contact 60 with said housing flange while closing the valve in said elongated tubular member.

3. An atomizer assembly comprising in combination an outer cylindrical housing member having a threaded inner cylindrical surface, an ex-

teriorly threaded portion adjacent the top thereof, and an inwardly presented flange adjacent the bottom thereof, an externally threaded central head in screw engagement with the inner threaded surface of the housing member and 5 adjustable axially by rotation therein to engage the said inwardly presented flange, said central head having an air vent extending substantially vertically therethrough, the lower opening of which is in alignment with said flange, said head further having a vertically projecting substantially centrally located shoulder through which is disposed a laterally extending passage, an elongated tubular member extending vertically through said head and having a constriction in 10 its upper end portion which projects above the head to provide a liquid passage of smaller diameter than that of said tubular member and to provide an inwardly disposed valve seat, a valve member adapted to engage said valve seat 15 and effect a closure of the tubular member when the said central head is brought into engagement with the housing flange, an air-conveying tubular member one end of which is adapted to fit within the lateral passage in the shoulder portion of the central head and to pass air across and at an angle to the constricted passage in the tubular member, and a tubular receptacle closed at its lower end extending through said central head and adapted to receive said air-conveying 20 tubular member.

4. A liquid-atomizing device capable of being sealed against leakage which includes in combination a liquid container having an opening in the upper portion thereof and an atomizing assembly fitting tightly in said opening, said atomizing assembly comprising in combination an outer cylindrical housing member having a threaded inner cylindrical surface, an exteriorly threaded portion adjacent the top thereof, and an inwardly presented flange adjacent the bottom thereof, an externally threaded central head in screw engagement with the inner threaded surface of the housing member and adjustable axially by rotation therein to engage the said inwardly presented flange, said central head having an air vent extending substantially vertically therethrough, the lower opening of which is in alignment with said flange, said head further having a vertically projecting substantially centrally located shoulder through which is disposed a laterally extending passage, an elongated tubular member extending vertically through said head and having a constriction in its upper end portion which projects above the head to provide a liquid passage of smaller diameter than that of said tubular member and to provide an inwardly disposed valve seat, a valve member adapted to engage said valve seat and effect a closure of the tubular member when the said central head is brought into engagement with the housing flange, an air-conveying tubular member one end of which is adapted to fit within the lateral passage in the shoulder portion of the central head and to pass air across and at an angle to the constricted passage in the tubular member, and a threaded closure cap adapted to engage the exterior threads on the cylindrical housing, and further adapted to engage the central head and by rotation to bring said head into closure contact with said housing flange while closing the valve in said elongated tubular member.

SOLON ALEXANDER DAVERON.
